UNITED STATES PATENT OFFICE

2,505,199

BODY CONSTRUCTION FOR STREET-SWEEPING MACHINES

Carl W. Mott, La Grange, Ill., assignor to Elgin Sweeper Company, Elgin, Ill., a corporation of Illinois

Application February 9, 1946, Serial No. 646,525

5 Claims. (Cl. 15—85)

1

This invention relates to improvements in street sweeping machines, and more especially to machines of this kind which are self-propelled.

Street sweeping machines have customarily been relatively heavy, massive and of expensive, complex construction so that the initial and upkeep cost have been high. In the smaller sizes of prior sweepers, moreover, the capacity and efficiency of the machines have not been up to what might be desired.

An important object of the present invention is to provide a small size or "baby" sweeping machine which can be produced and sold at low cost but which will nevertheless have a capacity and possess operating efficiency as great as or superior to much larger prior types of street sweeping machines.

Another object of the invention is to provide a street sweeping machine which is of unusually light weight construction and wherein a number of unique structural features and relationships contribute toward such result.

Still another object of the invention is to provide a small size street sweeping machine in which an unusual compactness of structural and operating features is attained.

A further object of the invention is to provide a small size street sweeping machine which can be produced and sold at a low price and which will operate at high efficiency and exceptionally low operating costs.

A still further object of the invention is to provide a new and improved street sweeping machine that is adapted to be built largely from sheet metal without the need for any additional main structure for supporting the operating mechanisms of the machine.

It is also an object of the invention to provide new and improved means in a street sweeping machine for gathering sweepings and to render the dumping of accumulated sweepings quick and simple.

Another and further object of the invention is to provide a new and improved street sweeping machine having novel facilities for disposal of sweepings.

It is a still further object of the invention to provide in a street sweeper novel dump door and operating mechanism therefor.

In accordance with the general features of the invention a self-propelled "baby" type of street sweeping machine is provided in which a front engine mount and cab structure is assembled with a rear main sweeper broom housing structure which is constructed virtually entirely from sheet

2

metal plates and is carried by the driving wheel structure.

According to other general features of the invention, the main broom housing, in addition to providing ample operating space for the main sweeping broom, serves also to support in compact arrangement a rearwardly inclined dirt box having its upper end located above the main broom to receive sweepings therein as deposited by a reciprocably mounted dirt bucket, and having its lower end located in the tail extremity of the sweeper housing where it is designed to facilitate dumping of accumulated sweepings and is closed by a rearwardly swinging dump door. There is also provided a compact arrangement of the sprinkling water tank and hose compartment above the dirt box and affording the top wall of the latter.

Another feature of the invention resides in the provision of improved pressure fluid operated mechanism, preferably hydraulic, and including a compound leverage disposed at the opposite sides of the rear portion of the broom housing structure for actuating the dirt box dump door.

Other objects, features and advantages of the present invention will be readily apparent from the following detailed description taken in connection with the accompanying four sheets of drawings in which:

Figure 1 is a side elevational view, in certain respects schematic, of a small size self-propelled street sweeping machine embodying the features of the invention.

Figure 2 is a slightly enlarged horizontal sectional view through the machine taken substantially along the line II—II of Fig. 1.

Figure 3 is a reduced scale, more or less schematic vertical sectional view, taken in substantially the plane of line III—III of Fig. 2.

Figure 4 is a fragmental vertical sectional view taken in substantially the plane of line IV—IV of Fig. 2 through the rear axle and wheel assembly.

Figure 5 is an enlarged fragmentary detail sectional view taken substantially along the line V—V of Fig. 3, and showing details of the dump door operating mechanism.

Figure 6 is a substantially enlarged fragmentary side elevational and sectional view of the dump door and which may be considered as taken substantially along the line VI—VI of Fig. 5.

Figure 7 is a fragmentary sectional detail view taken on substantially the plane of line VII—VII of Fig. 6.

Described generally, a "baby" street sweeper

embodying the features of the present invention comprises a front engine or power section 10 (Fig. 1) and a rear or sweeping section 11. The power section 10 comprises an operator's cab 12 and a forward engine housing 13 carried by a supporting frame or chassis 14 and is mounted for travel upon a front, steerable wheel 15 which may be a single wheel on a caster type of mount. The forward portion of the sweeping section 11 is secured in mutually supporting relation to the contiguous portion of the cab 12 and the chassis frame 14. At its lower rear portion the sweeping section 11 is supported by a pair of driving wheels 17 mounted for rotation upon a transverse axle 18.

According to the present invention, the sweeping section 11 comprises a combined housing and frame formed from sheet metal, the principal members of which are substantially symmetrical-ly formed left and right side plates 19 and 20, respectively, and a top plate 21 (Figs. 1, 2 and 3). The side plates 19 and 20 are formed with upper inwardly extending right angular reinforcing and supporting flanges 22, respectively, to which the side margins of the top plate are preferably secured as by welding. This provides a substan-tially inverted U-shaped housing, the forward margins of which are appropriately attached to the cab structure 12 and the engine supporting frame 14. The lower forward portions of the side plates 19 and 20 are preferably provided with re-spective forward wing extensions 23 for this purpose. No rear wall, as such, need be provided since the rear portion of the top plate 21 of the sweeper housing is for this purpose appropriately curved streamline fashion downwardly cooperatively with the rear edge portions of the side plates.

Support of the sweeping housing is effected di-rectly by the axle 18 through the medium of sleeves 24 (Fig. 4) carried by the axle inwardly of the wheels 17, each of the sleeves 24 being pro-vided with a radial flange 25 connected as by rivets 27 to the contiguous margins of the associated side plates 19 or 20, as the case may be. Additional reinforcement for the sup-porting area of each of the respective side plates is provided by a segmental flange 28 secured as by rivets 29 to the associated supporting sleeve 24 and making engagement with the associated side plate through an angle bracket 30 carried by the side plate.

Propulsion of the machine is effected in any preferred manner, such for example as by in-dividual chain drives 31 for the wheels 17 acting to drive the respective wheels through sprockets 32 attached to brake drums 33.

Within the sweeping housing provided by the rigidly united side plates 19 and 20 and the top plate 21 is operatively disposed a main sweeping broom 34 (Figs. 1 and 3) of preferably the cylindrical, rotary bristle type, a dirt bucket 35, a dirt box 36, a water tank 37, and various appur-tanences to effectuate the operation and control of these various devices.

The main sweeping broom 34 is accommodated transversely within the lower portion of the sweeping housing 11 and in compact relation im-mediately forwardly of the axle 18 and partially between the wheels 17. Side arms 38 carry the broom and are pivotally secured at their forward ends to a rock shaft 39 by which the broom can be elevated for disposition out of service and which permits vertical adjustment of the broom to compensate for wear. In order to facilitate as-

sembly of the broom 34 within the sweeping housing, each of the side plates 19 and 20 is formed with a lower longitudinal clearance cut-out 40 so that the broom can be assembled or re-moved by longitudinal movement thereof laterally of the housing clear of the wheel 17 at the side where such maneuver takes place. Means for driving the sweeper broom 34 rotatably counter-clockwise as seen in Fig. 1 may comprise a sprocket chain 41 meshing with an appropriate sprocket 42 on the broom shaft.

The dirt bucket 35 is at least as wide as the main broom 34 and is suspended rigidly at its ends by respective arms 43 with its mouth opening to-ward the broom and in such position immediate-ly in front of the broom as to efficiently receive sweepings propelled thereto by the broom. The bucket-supporting arms 43 are over the space occupied by the broom 34 and are accom-modated between the side plates 19 and 20 and the sides of the dirt box 36 at their rear ends, the arms 43 are secured fast upon radial flanges 44 on respective journalled sleeve brackets 45 rotatably and detachably mounted upon the axle 18 im-mediately inwardly of the side plate sleeve brackets 24. A retaining collar 46 may be dis-posed about the axle 18 at the inner end of the hub of the rotary bracket 45.

In the operation of the machine, the arms 43 are swung up periodically to dump the contents of the bucket 35 into the dirt box 36. For this purpose, each of the rotary brackets 45 has a rearwardly projecting bifurcated ear 47 (Fig. 3) to the rear end portion of which is operatively connected a hydraulic actuator 48 in the form of a conventional cylinder and piston (Figs. 3 and 5), the upper end of the cylinder being supported pivotally by a pin structure 49 extending between and supported by the respective adjacent side plate 19 or 20 and the opposing side wall of the dirt box 36. For a more detailed description of the construction and operation of the dirt bucket 35, reference may be had to my copending appli-cations Serial No. 680,041, filed June 28, 1946; and Serial No. 697,269, filed September 16, 1946 and now abandoned.

Means for guiding the dirt bucket 35 in the arcuate path which it describes in traveling from the dirt collecting position to the dumping po-sition may comprise rollers 50 (Figs. 2 and 3) mounted at the upper sides of the bucket and guidingly engaging arcuate bearing plates 51 mounted on the respective side plates 19 and 20.

In front of the operating path of the dirt bucket 34 is a dirt shield 53 which, as best seen in Figs. 1 and 3, preferably extends arcuately upwardly between the side plates 19 and 20 and to a point adjacent the top plate 21. The shield 53 may be formed from a single sheet of metal and is secured to the side plates in any suitable fashion, as for example by means of appropriate angle irons 54 which are welded to the shield plate and to the respective side plates. In addition to serving as a dirt shield, the plate 53 also serves as a trans-verse forward reinforcement between the side plates and contributes in a substantial measure to the strength of the housing and supporting frame structure.

An efficient disposition of the dirt box 36 is at-tained by disposing the mouth thereof above the main broom 34 to provide an ample working space therefor and in such a position that when the dirt bucket 35 is elevated to dumping position, as indicated in broken outline in Fig. 3, the contents 75 of the substantially inverted bucket will be re-

ceived in the dirt box. At the upper sides of the dirt box 36 are laterally diverging guard wings 55 to receive the sides of the bucket therebetween and avoid side spill of dirt dumped into the box.

From its mouth, the dirt box 36 extends diagonally rearwardly down over the main broom 34 and over the axle 18 to the bottom rear extremity of the sweeping section 11 where the discharge end of the dirt box is closed by a dump door 56. By preference, the dump door 56 constitutes a substantial lower end extension of the dirt box 36 whereby to increase the capacity of the dirt box, while at the same time blending into the general streamline contour as the tail portion of the sweeping section 11.

The dump door 56 is mounted to be swung open rearwardly and upwardly and is therefore hingedly secured to the rear edge of the top plate 21, as by means of a piano type hinge 57. The width of the dump door 56 is preferably such that the side edges of the dump door abut the rear edges of the side plates 19 and 20, substantially as indicated in Fig. 5. This affords space between the sides of the dirt box 36 and the inner side walls of the dump door for door-actuating mechanism. In the present instance, such mechanism includes a hydraulic operator 58 of cylinder and piston type, the cylinder of which is pivotally secured at 59 between the adjacent side plate and the dump box and the piston rod of which is pivotally secured through a knuckle 60 and a pin 61 between a pair of parallel links 62. These links have their forward ends secured pivotally by a pin 63 between the inner side of the upper portion of the dump door 56 and a rigid parallel inwardly spaced supporting plate 64. From the piston rod connection 61, the pair of links 62 extends to a greater distance forwardly than they do rearwardly and are secured at their forward ends by a pin 65 pivotally to the end of a tilting link 67, the opposite end of which is secured fast upon the end of a connecting rock shaft 68. By preference, the tilting link 67 is adjustable as to length and for this purpose is provided as an assembly with an adjusting stud 69. When the piston rod of the hydraulic operator 58 is protracted, the dump door operating linkage system assumes substantially the position indicated in broken outline in Fig. 3 to open the dump door 56 and swing it sufficiently high to assure complete discharge therefrom of dirt lodged therein from the bottom of the dirt box.

Since the dump door 56 is wider than the dirt box, a shield 70 (Figs. 6 and 7) is provided to extend diagonally inwardly from each side of the dump door for engagement with the adjacent side of the dirt box for confining the sweepings descending from the lower end of the dirt box to the rearwardly bulging receptacle portion of the dump door and prevent the sweepings from crowding forwardly out of the dump door into the space between the dirt box and the forward portions of the side walls of the dump door.

At its extremity, the dump door 56 substantially engages the lower corner extremity of the dirt box 36. Thus, a reasonably tight closure is provided by the dump door 56, and this is assured by the operation of the door operating linkage system. By the particular relationship of the operating links 62 and 67, together with the connection 60, 61 with the hydraulic operator 58 disposed rearwardly of the center of the links 62 when the piston rod of the hydraulic operator is fully retracted, the linkage tightly draws the door 56 into closed relation to the dirt box. The

beyond-center connection of the operator and links 62 effects a substantially locked condition of the lever system. In the closing of the door 56, any slight looseness or sidewise deflection that might cause faulty registration is cured by the provision of interleaving guide fingers 72 and 73 provided, respectively, on the inner side margin of the dump door and the adjacent side plate 19 or 20.

10 The space between the dirt box 36 and the rear portion of the top plate 21 of the housing is utilized for housing the water tank 37. In fact, the bottom of the water tank 37 may, as shown, be utilized as the upper diagonal wall of the dirt box. By preference, also, the water tank 37 supports the dirt box 36 and for this purpose is provided with side plates 74, the respective lower margins of which extend below the bottom of the water tank and are secured to the upper margins of the dirt box side walls as for example by riveting 75. The top wall of the water tank may be the overlying and enclosing portion of the top plate 21 of the housing and frame structure of the sweeping section. In this way, 15 the water tank and the dirt box are substantially supported by the housing and frame structure through the top plate 21 thereof. The dirt box 35 and the water tank 37 are preferably formed from sheet metal. Lateral stability of the suspended dirt box and water tank structure and reinforcement of the entire sweeping section frame is afforded by a transverse member 76 which may be a strong angle bar secured to the lowermost margin of the dirt box and rigidly attached at its 20 ends to the inside of the side plates 19 and 20.

35 A space rearwardly of the lower end of the water tank 37 and above the lower end of the dirt box 36 inside the upper portion of the dump door 56 is adapted to be utilized as a hose compartment 77 (Fig. 5) for supporting the hose (not shown) by which the water tank 37 is filled from any available hydrant in the customary manner. The bottom of this compartment is defined by a floor plate 78 and opposite side deflector plates 79. 40 The floor plate 78 serves also as the rear portion of the roof for the dirt box 36. Access into the hose compartment is preferably by way of a hose compartment door 80 (Fig. 2) provided for this purpose in the upper portion of the dump door 56 and utilizing the central portion of the hinge 57. Thus, the hose compartment access door 80 will swing with the dump door 56 in movements of the latter, but may be opened independently of the dump door when access is desired to the water tank filling hose.

45 Appropriately shaped removable side guard plates 81 and 82 are mounted exteriorly of the housing side plates 19 and 20, respectively, and provide an attractive enclosure for the wheels 17 and the drive chains 38 therefor, as well as the 50 sweeper broom supporting arms 39 and drive chain 41. Each of the side closure plates 81 and 82 may be constructed as a relatively rigid self-sustaining unit having a right angular reinforcing and spacer flange 83. Vertical strut structure 84 extends up in supporting relation at the front end of each of the flanges 83 and is secured to the contiguous side plate.

55 A splash guard in front of and partially overlying the main broom 34 may be provided by a plate 85 (Figs. 1, 2 and 3) which is suspended from the lip of the dirt box 36 by an integral rearwardly angled flange 86. Downwardly projecting pins 87 on the flange engage loosely in appropriate apertures 88 in the dirt box lip and re-

strain the splash guard 35 against dislodgement. At its lower end the splash guard is connected to forwardly extending pivoted side links 39 which are pivoted on the respective side plates 19 and 20 and hold the splash guard in proper forwardly inclined relation closely in front of the main broom 34.

When it is necessary to afford full clearance in front of the main broom for assembly or removal thereof, and the dirt bucket 35 has been elevated out of the way, the splash guard 35 is adapted to be swung forwardly into full clearance by pivotally swinging the lower end thereof up and forwardly on and with the links 39 from the full line to the broken line position shown in Fig. 3. In the course of such swinging of the splash guard its upper end portion slides freely on the dirt box lip, with the retaining pins 37 leaving their apertures 38 and returning thereto in accordance with the position of the splash guard.

While the splash shield 35 intercepts forward splash above the dirt bucket 35, the bottom wall of the dirt box 36 provides a rearward splash shield for the main broom space.

Suitable side guard shoes 33 may be mounted at the opposite sides of the sweeper broom 34 and extend forwardly therefrom to close the side spaces between the sweeper broom and the dirt bucket 35.

Forwardly of the dirt bucket 35, a rotary side broom 91 is preferably mounted to be driven by the same source of power as the main broom 34, in a manner disclosed in more detail in my co-pending application Serial No. 687,460, filed July 31, 1946. A dirt guard or baffle 92 extends in front and inside of the side broom 91 and is carried by a supporting structure 93 depending from the supporting frame 14.

From the foregoing, it will be apparent that the present invention provides a street sweeping machine of unusually compact, simple, and light weight construction. The novel structure of the sweeping section 11 of the machine, which is made substantially entirely from relatively light weight sheet metal, contributes very largely to the improved results attained. Not only is the initial cost of the machine rendered relatively low by reason of the various economical relationship and devices provided in this machine but the upkeep cost is also minimized. In spite of its very compact, small size, the machine has an unusually large working capacity because of the economical utilization of available space.

It will, of course, be understood that various details of construction may be varied through a wide range without departing from the principles of this invention and it is, therefore, not the purpose to limit the patent granted hereon otherwise than necessitated by the scope of the appended claims.

I claim:

1. A self-propelled street sweeping machine comprising, in combination, a front power unit and cab section including a supporting steerable wheel, a rear sweeping section including a substantially inverted U-shaped supporting frame and housing structure having its axis disposed longitudinally and secured to the front section and having a transverse supporting axle engaging the lower rear portion thereof and carrying propelling road wheels having driving connections with the power unit, a main sweeping broom disposed forwardly of said axle between the road wheels and having supporting arms and driving means connecting the same with said front sec-

tion, a dirt bucket disposed forwardly of the main broom and having carrying arms pivotally mounted on said axle and adapted to swing the bucket arcuately upwardly inside of said housing into a substantially inverted position above said main broom, a dirt box supported by said housing structure and having its mouth above the main broom positioned to receive dirt dumped thereinto from said dirt bucket, the dirt box extending in a downwardly slanting rearward direction to the rear of said axle, a dump door mounted on said housing structure and swingable into and out of closing relation to the lower end of the dirt box, and means within the housing for actuating said dirt bucket and said dump door.

2. A self-propelled street sweeping machine comprising, in combination, a front power unit and cab section including a supporting steerable wheel, a rear sweeping section including a substantially inverted U-shaped supporting frame and housing structure secured to the front section and having a transverse supporting axle engaging the lower rear portion thereof and carrying machine-propelling road wheels having driving connection with the power unit, a main sweeping broom disposed forwardly of said axle between the road wheels and having supporting arms and driving means connecting the same with said front section, a dirt bucket disposed forwardly of the main broom and having carrying arms pivotally mounted on said axle and adapted to swing the bucket arcuately upwardly inside of said housing into a substantially inverted position above said main broom, a dirt box supported by said housing structure and having its mouth above the main broom positioned to receive dirt dumped thereinto from said dirt bucket, the dirt box extending in a downwardly slanting rearward direction to the rear of said axle, a dump door mounted on said housing structure and swingable into and out of closing relation to the lower end of the dirt box, means within the housing for actuating said dirt bucket and said dump door, and dirt shielding and splash guard means in spaced relation at the front and the rear of the path of movement of the dirt bucket.

3. In combination in a street sweeping machine of the character described, a substantially inverted U-shaped housing and frame structure including a top plate and a parallel pair of side plates, a dirt box structure suspended from said top plate and having the side walls thereof in spaced relation to said side plates, the dirt box having its lower wall spaced throughout at least its major extent above the lower edges of said side plates and cooperating with said side plates to provide a main sweeping broom space below said lower wall, a main sweeping broom extending transversely of the machine in the main sweeping broom space and a dirt bucket disposed on the discharge side of the main broom to receive the discharge therefrom and having supporting arms, said arms being located to swing up and down in the space between the dirt box and said side plates for carrying the dirt bucket from dirt collecting position into dumping position at the top of the dirt box.

4. In combination in a street sweeping machine of the character described, a substantially inverted U-shaped housing and supporting structure including a top plate and a parallel pair of side plates, a dirt box structure suspended from said top plate and having the side walls thereof in spaced relation to said side plates, the dirt

box having its lower wall spaced throughout at least its major extent above the lower edges of said side plates and cooperating with said side plates to provide a main sweeping broom space below said lower wall, a main sweeping broom extending transversely of the machine in the main sweeping broom space, a dirt bucket having supporting arms, said arms being located to swing up and down in the space between the dirt box and said side plates for carrying the dirt bucket from dirt collecting position on the discharge side of the sweeping broom into dumping position at the top of the dirt box, and means supported in said space between the housing and said dirt box side walls for actuating said supporting arms.

5. In combination in a street sweeping machine of the character described, a substantially inverted U-shaped housing including a top plate and a parallel pair of side plates, supporting wheels, an axle for said wheels and having journal means secured to said side plates and thereby supporting the housing, a dirt box structure suspended from said top plate having its mouth adjacent said top plate and having the side walls thereof in spaced relation to said side plates, the dirt box having its lower wall spaced above said axle and above the lower edges of said side plates to afford a main sweeping broom space below said lower wall, a main sweeping broom in said space, and a dirt bucket having supporting arms pivotally mounted on said axle and adapted

to swing up and down about the axis of said axle in the space between the dirt box and said side plates for carrying the dirt bucket from dirt collecting position on the discharge side of the sweeping broom space into dumping position at the mouth of the dirt box.
